CLAIM

The ornamental design for a multifunction printer, as shown and described.

DESCRIPTION

FIG. 1 is a front view of a multifunction printer according to my new design;

FIG. 2 is a back view thereof;

FIG. 3 is a top view thereof;

FIG. 4 is a bottom view thereof;

FIG. 5 is a left view thereof;

FIG. 6 is a right view thereof;

FIG. 7 is a perspective view thereof; and,

FIG. 8 is an enlarged view of the portion of FIG. 1 defined by arrows A and B.

The dashed broken lines illustrate portions of the multifunction printer that form no part of the claimed design. The dash-dot broken lines indicate a boundary of the design that forms no part of the claimed design.

1 Claim, 8 Drawing Sheets
